BEDPAN COMMODE

William S. Horn, Fort Worth, Tex.

Application February 10, 1948, Serial No. 7,400

3 Claims. (Cl. 155—31)

1

This invention relates to devices for caring for invalids and hospital patients, and other incapacitated persons, and it has particular reference to a portable bed-height commode which is especially adapted for use in hospitals, and other similar institutions, caring for bed patients unable to move about freely, and its principal object resides in the provision of a light frame structure, preferably of a light tubular material, designed to conveniently support a conventional bed pan commonly used in the care of bed patients, so that such devices may be utilized by patients able to remove themselves, either by their volition or by the aid of attendants, to a position upon the device which may be arranged at the bedside of the patient, and affording a medium which will readily accommodate the patient with a minimum of exertion on his part while also minimizing the necessity of assistance by attendants.

It is an object of the invention to provide a compact and light structure possessing the features of a conventional commode having a comfortable open seat which may be provided with a hinged cover capable of being used, in closed position, as a bed table or stand affording a convenient support for other objects as may be desired.

It is a further object of the invention to provide an attractive article having features which serve to enclose the bed pan and its attaching devices so that it may have the appearance of an ordinary bedside stand and, being light in structure and compact in form, may be easily and readily ported about a room or between rooms in a hospital, or other similar institutions, with a minimum of effort and time.

Broadly, the invention contemplates the provision of a simple arrangement whereby incapacitated persons may be conveniently cared for with the least amount of effort on the part of the patient, as well as the attendant, while affording other utilitarian purposes, and includes the provision of apparatus which may be utilized as a conventional seat-high commode if desired.

While the foregoing objects are paramount, other and lesser objects will become manifest as the description proceeds, taken in connection with the appended drawings wherein:

Figure 1 illustrates the preferred form of the invention in vertical section, taken on lines 1—1 of Figure 2, showing the open seat and hinged cover therefor, and illustrating the foot stand forwardly of the main frame structure, a conventional bed pan being shown in dotted lines.

Figure 2 is a plan view of the invention, illustrating the open seat, and showing the cover in lateral cross-section.

Figure 3 is a fragmentary cross-sectional view from the rear of the invention showing the bed

pan supports and the clamp detachably securing the same.

Figure 4 is a fragmentary side elevational view of the invention showing the cover in raised position and illustrating padding thereon in dotted lines.

Figure 5 is a fragmentary perspective view of the cam assembly for retaining the bed pan in position beneath the seat.

Figure 6 is a side elevational view of a modified form of the invention showing a hinged foot stand, a handling device, and porting casters detachably secured to the rear legs.

Figure 7 is a perspective illustration of the invention modified to afford a seat-high structure, and

Figure 8 fragmentarily shows the upper end of the invention, in side elevation, illustrating a detachable guard rail on one side.

Accordingly, the invention comprises a light frame structure which consists, in its preferred form, of a plurality of legs 10, preferably of a tubular material, and of such length as to be of convenient height for hospital beds which are conventionally higher than beds for common use, providing a convenient bed-height commode for bed-ridden patients and invalids incapable of freely moving about. The legs 10 are connected at spaced levels by rungs 11 and across their tops by cross-members 12 and 13.

The preferred form of the invention is shown in Figures 1 and 6 and provides a structure having the desired height for the accommodation of hospital patients, and invalid persons in other similar institutions. By reason of such height it is desirable to provide a foot stand 14 forwardly of the frame structure which has a firm upper surface 15 preferably covered by a rubber mat 16, or the like, to prevent persons from slipping or skidding while standing thereon, as shown particularly in Figures 1 and 2. Obviously, however, the foot stand may be hingedly connected to the main stand in the manner illustrated in Figure 6 which will presently be described.

An open seat 17 is attached to the members 12 and 13 at the top of the legs 10 and is adapted to be closed by a cover 18 which is hinged at a to the back of the seat 17, as shown particularly in Figure 1. When the cover 18 is closed, as shown in Figure 1, a convenient bedside table is provided. In a modification of the structure, as in Figure 4, the underside of the cover may be afforded padding 19, indicated in dotted lines, to provide a comfortable back support for persons supported on the seat 17.

Depending below the seat 17 is a substantially U-shaped bracket 20 forwardly of the frame, as shown in Figures 1 and 3, having its legs attached to the underside of the seat 17, and supports the forward end of a conventional bed pan 21 illus-

trated in dotted lines in Figure 1. Spaced rearwardly from the bracket 20 are a pair of spaced supports 22 which depend from the seat 17 in much the same manner as the bracket 20. Rotatably connected between the members 22 is a horizontally arranged rod 23 to which is rigidly connected one end of a tensioned cam 24 which, in its operative position illustrated in Figure 1, bears upwardly against the underside of the rear end of the bed pan 21 to removably secure the same in position as in Figure 1. The outer end 25 of the cam 24 projects rearwardly of the frame structure and is conveniently accessible to be manipulated downwardly by an attendant to release the bed pan 21 so that the latter can be removed from its support without raising the cover 18 or removing the seat 17.

The bed pan 21 and its supports 20 and 22, including the cam 24, are closed on all, except the rearmost side, by a depending apron 26. It is desirable that the apron 26, as well as the other parts, excepting the seat 17, be of such material as aluminum, stainless steel, or other suitable materials.

The cover 18 may be provided with any convenient type of stop to limit its backward movement and support the same in a position slightly rearwardly from the vertical, as illustrated in Figure 4, to provide a suitable back rest for a person reposing upon the seat 17. A pair of links 27 are pivotally connected at b to the side rim of the cover 18 while the opposite ends c are slidably connected to a slotted bracket 28 fixed on each side of the seat 17, as illustrated in Figures 4 and 7.

In Figure 6 the structure illustrated is similar in all respects to that illustrated in Figure 1 except that the foot stand 14 is replaced by a hinged support 29 which is hingedly connected at d to the front legs 30 and supported at its outer end by a hinged brace 31 pivotally connected to the outer edge of the support 29 at e and near the bottom of the front legs 30 of the structure at f. In this form of the invention the lowermost ends of the front legs 30 have forwardly extending feet members 32 which serve to prevent the structure from tilting forwardly when weight is applied to the support 29 by persons stepping or standing on this member. The front legs 30 and the rear legs 33 are connected at spaced levels by rungs and cross-members 34 similar to the members 11 of the structure shown in Figure 1. The cover 18 and the apron 26 are also applied to this structure.

Obviously, the invention may be constructed according to the modification illustrated in Figure 7 wherein is shown a frame structure which has legs 35 and 36 of convenient seat-height and may be utilized for ordinary convenience where bed-height commodes are not required. An open seat 37 is provided which may be formed exactly like the seat 17 previously described and illustrated in Figure 1. A hinged cover 38 covers the seat 37 and has sliding hinged brackets 39 on each side to support the same in upright position, as shown in Figure 7. The apron 26 is employed in this structure serving to enclose the bed pan 21 in the same manner as in the structures shown in Figures 1 and 6.

If it is desired to afford a more readily portable device, a pair of casters 40 may be secured to the rearmost legs 33 of the frame, as shown in Figure 6. The casters 40 may be mounted in clamps 41 capable of being detachably secured with suitable bolts 42 to the lowermost ends of

the legs 33 so that the casters 40 extend rearwardly thereof, when the device is stationary to avoid moving about voluntarily while in use. The entire structure may be tilted back so that the legs are clear of the floor and the invention is supported by the casters 40.

A handling bar 43 can be provided having its ends detachably inserted in sockets 44 on the upper ends of the legs 33, thus affording a means for conveniently handling or porting the invention about. Another bar, or guard 45 is provided for detachable securement to the side of the frame structure, as shown in Figure 8, to afford security for weakened persons using the device.

It is not contemplated that the invention be limited to the structure herein shown and described beyond the limitations imposed by the prior art and the scope of the appended claims.

What is claimed is:

1. In a portable commode for invalids, or the like, in combination, a supporting stand of suitable bed height having a foot support of lesser height formed therewith, an open seat arranged on said stand and a hinged cover for said seat, the said cover providing a bed-side table, supporting means for a bed pan arranged beneath said seat comprising a bracket suspended therebelow, a rod spaced rearwardly from said bracket and suspended from said seat, and a tensioned clamp operatively secured to said rod for removably securing a bed pan beneath said seat.

2. In a hospital commode, in combination, a tubular frame structure having legs of suitable hospital bed-height length, a foot stand formed with said frame and having lesser height, an apron depending from the front and sides of said frame, an open seat arranged on the top of said frame, a hinged cover for said seat providing a bed-side table when closed, supporting brackets for a bed pan depending beneath said open seat, one set of said brackets having a rod connecting the same, and a tensioned clamp operatively attached to said rod removably securing a bed pan thereon beneath said seat.

3. In a combination bed table and invalid commode, in combination, a stand of suitable hospital bed height having legs, a step formed on one side of said stand having legs of lesser height than the legs of said stand, an open seat arranged on said stand and a hinged closure for said seat adapted to be closed thereupon providing a table surface, an apron depending below said seat at each side and in front of said frame providing an enclosure, a supporting bracket arranged beneath said seat and forwardly thereof for operatively supporting one end of a conventional bed pan within said enclosure, and tensioned clamp means pivotally supported rearwardly of said seat removably retaining said bed pan on said supporting brackets.
